W. W. Smith

Harness Buckle.

No 11336

Patented July 18, 1854.

UNITED STATES PATENT OFFICE.

W. W. SMITH, OF MARSHALL, MICHIGAN.

BUCKLE.

Specification of Letters Patent No. 11,336, dated July 18, 1854.

To all whom it may concern:

Be it known that I, WILLIAM W. SMITH, of the village of Marshall, in the county of Calhoun, in the State of Michigan, have invented a new and Improved Buckle, called the "Tug-Hook Buckle" and to be used in other places besides on tugs; and I do hereby declare that the following attached drawing is a full and clear description of the same, viz:

"A" represent the band of said buckle which is round and made of metal, with the exception of space from 1 to 2 which is flattened to make a bed for the leather.

"B" is the hook or tongue, which is cast solid or stationary with the band.

What I claim as my invention, and desire to secure by Letters Patent is—

The stationary hook or tongue attached to the body of the buckle substantially as above described and shown as an improvement on the old or loose tongue and buckle, not only in the cheapness of manufacturing them but in their strength and durability, and the ease with which they are or can be buckled and unbuckled.

W. W. SMITH.
